UNITED STATES PATENT OFFICE

GERHARD FLINTERMANN, OF WEST ORANGE, NEW JERSEY

SEAT

Application filed May 8, 1929. Serial No. 361,405.

This invention relates to seats and has for an object the provision of an improved convertible seat. More particularly the invention contemplates the provision of an improved seat of the type used in sleeping cars. The invention further contemplates the provision of an improved couch or bed which may be formed through the combination of two convertible seats.

- 10 According to some present practices seats provided in relatively small spaces such as sleeping cars are so constructed that portions of two adjacent seats are adjustable in position and the two seats may be combined to form a bed or couch for reclining or sleeping. Thus, in railway sleeping cars, adjacent seats are so constructed and arranged that the bottom cushions may be drawn together to form a substantially continuous supporting surface over the aisle between the seats. The back cushions may be moved into the spaces made vacant by the moving of the bottom cushions on fixed, non-resilient supports and the cushioning effect has been obtained largely through springs in the cushions. Also, in some instances, the bottom cushions are so mounted that when drawn out their bottom edges extend substantially horizontally with the result that the front portions are disposed at higher elevations than the rear portions, by virtue of the fact that the bottom cushions are thicker at the front than at the rear, and a transverse ridge is produced in the resulting bed or couch. The front faces of the bottom cushions are closely adjacent when the cushions are extended and even if the cushions should be mounted on resilient supports downward flexing of the central portion of the resulting bed would be prevented.
- 20 The present invention contemplates the provision of seats in which the bottom cushions are so mounted that they are resiliently supported. The invention further contemplates the provision of seats which may be converted into beds without the production of objectionable ridges. The invention further provides for the production, from two seats, of a bed in which the central portion is comfortably flexible.
- 25 Seats constructed in accordance with the

present invention comprise an adjustable support for the bottom cushion which is so mounted that when the cushion is drawn forwardly the rear portion is raised and the front portion is lowered. The adjustable support may be mounted on resilient supporting means which further add to the comfort of the bed or couch produced, and which permit flexing of the resulting bed or couch.

The invention will be better understood from a consideration of the following description in conjunction with the accompanying drawings in which:

Fig. 1 is an elevation of a bed and seats embodying the invention and showing the bottom seat cushions and supports in their extended positions;

Fig. 2 is a plan taken substantially along line 2—2 of Fig. 3 and showing the adjustable support with a portion of the transverse brace broken away;

Fig. 3 is an elevation taken substantially along line 3—3 of Fig. 2 and showing a bottom cushion and support in their normal retracted positions;

Fig. 4 is an elevation taken substantially along line 4—4 of Fig. 2;

Fig. 5 is an elevation taken substantially along line 5—5 of Fig. 2; and

Fig. 6 is an elevation taken substantially along line 6—6 of Fig. 2.

The drawings show apparatus constructed in accordance with the invention as applied to a railway sleeping car. The wall side being at the left in Fig. 4 and at the bottom in Fig. 2, and the space for the usual steam and other pipes being indicated at 10. The seats are provided with the usual arm rests 11 and supports 12 on the aisle side, and the usual rear partition 13 which supports the back cushion.

Rigid supporting ledges 14 in the form of metal plates are carried by the side supports and project inwardly to provide means of attachment for resilient cushioning members 15. The plates 14 on the wall side are rigidly attached to the wall side supports 18 which have horizontal top portions extending over the foot rest 9 and vertical side portions attached to the horizontal top portions and

the floor. The plates 14 on the aisle side are rigidly attached to the aisle side supports 12.

Each cushioning member 15 comprises a 5 pair of outer channel shaped sheet metal members 17 having their ends spaced apart by means of shims 19 and held in fixed relative positions by means of bolts 20. The channel members enclose an annular soft rubber body 21 which may be formed of two U-shaped parts. An annular channel-shaped metal core 22 corresponding in outline to the opening in the rubber body is mounted within the opening in the rubber body with its 10 side edges spaced from the side edges of the outer channel members 17. The plates 14 extend into the central openings in the channel members 22 and are rigidly attached to said members. The upper portion of the rubber body 21 is thicker at the rear than in front and the lower portion is thinner at the rear than in front, in order to provide the greatest cushioning effects at the most effective points.

20 A angle iron 24 is attached to each cushioning member 15 with one web lying in contact with the upper surface of said member and the other web extending downwardly vertically on the inside. The angles 24 are attached by means of bolts or rivets 25 to the upper one of the members 17 and to the lower one of the members 17 by means of a bolt 26 extending through an opening in the center of the cushioning member. The main portion of the upper surfaces of the angles 24 normally extend substantially horizontally and the rear portions extend upwardly to maintain the top of the back cushion in an elevated position when the bottom cushion 30 is extended and the back cushion is in position to form a bed. An angle iron 28 is attached to and extends between the rear ends of the angles 24 to provide means for confining the back cushion in its proper position in a bed structure. The horizontal portions of the angles 24 are preferably sufficiently long to support the bottom cushion in its normal position in a seat structure, the angles 24 extending upwardly rearwardly of the bottom cushion.

50 A cushion support comprising side members 27 and a front transverse brace 30 is adjustably mounted on the angles 24. The members 27 and 30 are preferably angle irons. 55 Each of the side members 27 is mounted with a web lying in contact with the downwardly extending web of an angle 24, and supported at the rear by a bolt 31 and at the front by a cylindrical pin 32. The pins 32 are rigidly mounted on the angles 24, and the lower edges of the downwardly extending webs of the side members 27 are provided with semi-circular slots 29 for the reception of said pins. 60 Each member 27 is provided with two semi-circular slots 29, one adjacent the front end

and one adjacent the center. The bolts 31 are carried by extensions of the downwardly extending webs of the members 27 and extend through slots 33 in the angle irons 24. The slots 33 are so formed that their bottom walls extend forwardly and upwardly so that when a support with the cushion thereon is drawn forwardly the rear end of the cushion moves upwardly. A suitably bent piece of sheet metal 34 is rigidly attached to each angle iron 24 on the inside to provide guides for the side members 27.

70 The cushion supports are provided with upwardly projecting pins 35 which are adapted to enter corresponding recesses in the bottoms of the bottom cushions 36. In the seat structures, the front edge portions of the bottom cushions project beyond the front edges of their supports.

75 Fig. 1 shows a bed structure formed by combining two adjacent seat structures. The cushioning supports are shown drawn forwardly with their rear ends raised and their front ends depressed. The lowermost edges 80 of the front portions of the back cushions 37 and bottom cushions 36 are shown to be at lower elevations than the lowermost edges of their rear portions. The central portions of the upper surfaces of the back and bottom cushions are at the greatest elevations, and these portions all lie in a single substantially horizontal plane. The mattress 38 lies in contact with only the central portions of the upper surfaces of the back and bottom cushions when the bed structure is not in use.

85 The bed structure of the invention comprises two separate floating platforms which may move independently of one another. The bottom cushion supporting means of each seat structure comprises an extensible platform resiliently supported adjacent its front edge portion when in its retracted position and resiliently supported adjacent its center and having two free or floating ends 90 when in its extended position. When the extensible platforms are in their extended positions, the cushioning members 15 permit limited pivotal action. Thus, when a force acts downwardly on the central portion of the bed structure, downward movement of that portion is resiliently resisted by the lower front portions and the upper rear portions of the rubber cores 21. The extent of flexing of the bed structure may be varied by varying the sizes of and the types of materials used in the resilient cores 21.

100 The bed structure provides maximum comfort. The heavier portions of a sleeping or reclining person are disposed over the central portion of the bed which may be sufficiently flexible to absorb or minimize all shocks.

105 I claim:

110 1. A seat comprising a frame, a rigid support therefor, resilient supporting means in-

terposed between said frame and said rigid support and connecting the same, a cushion support and horizontally extending means for slidably connecting said cushion support to said frame whereby said cushion support may be moved in a direction from front to rear of the seat to change the horizontal relationship between the cushion support and the resilient means.

10 2. A seat comprising a rigid support, a seat frame, resilient supporting means interposed between said rigid support and said frame and connecting the same, a cushion support, and a slidable connection between said cushion support and said frame and having a part disposed at an angle to the horizontal whereby said cushion support may be moved on said frame to change the horizontal relationship between said cushion support and said resilient supporting means and whereby the angle of said cushion support may be changed as said cushion support is moved on said frame.

3. A seat comprising a rigid support, a frame, resilient supporting means interposed between said rigid support and said frame and connecting the same, a cushion support, horizontally extending means for slidably connecting said cushion support to said frame whereby said cushion support may be moved in a direction from front to rear of said seat to change the horizontal relationship between the cushion support and said resilient supporting means and means for locking said cushion support in different positions on said frame.

In testimony whereof I affix my signature.

GERHARD FLINTERMANN.
